ATTORNEYS

UNITED STATES PATENT OFFICE.

KENNETH WILLIAM MACPHERSON, OF PALMYRA, NEW YORK.

INK-ERADICATOR.

1,153,807.

Specification of Letters Patent. Patented Sept. 14, 1915.

Application filed November 11, 1914. Serial No. 871,498.

To all whom it may concern:

Be it known that I, KENNETH W. MACPHERSON, a citizen of the United States, and a resident of Palmyra, in the county of Wayne and State of New York, have invented certain new and useful Improvements in Ink-Eradicators, of which the following is a specification.

My invention relates to ink eradicators, and the main object thereof is to provide a container for each of the two liquids used in ink eradication and forming, jointly, a unit adapted to be carried in the pocket, handbag, or the like.

15 A further object is to provide each container with a valve, the stem of which projects beyond the container, whereby the said liquids may be applied directly to the ink which it is desired to eradicate in the manner of writing.

20 A further object is to combine the container with any one of the usual implements carried by a person in his pocket, such as a fountain pen, a pencil, a knife, a scratcher, or the like, in such manner as to enable a person to use each liquid at will.

25 A further object is to provide means for locking the container, in such combined use, in either of its two operative positions; and further objects are to provide such devices which are simple in construction and use, which are well adapted to the purpose for which they are designed, which may be made very ornate, which are compact and 35 always ready for use, and which are comparatively inexpensive.

30 My invention is fully described in the following specification, of which the accompanying drawings form a part, in which like reference characters indicate like parts in each of the views, and in which:—

Figure 1 is a side view of my invention applied to a fountain pen; Fig. 2 is an enlarged, sectional, detached, view thereof; 45 and Fig. 3 is a detached view of a valve which I employ.

In the drawings forming a part of this application I have shown a present preferred form of embodiment of my invention, 50 comprising a cylindrical block 4 having a central flange 5 thereon, and screw threaded at each end, as shown at 6 and 7, to receive similarly screw threaded cups 8 and 9, respectively, said block having a central, longitudinal, bore 10 at each end, and two diametrically arranged bores 11 in the

flange 5, and a longitudinally arranged slot 12 in the position of each bore 11.

The cup 8 has a chamber 13 therein of conical formation at 14 to form a seat for a conical valve 15 and the stem 16 of which is grooved or flattened at 17 and slidable in a bore 18 of said cup, a coil spring 19 being interposed between the valve and corresponding end of the block 4 and guided by means of a rod 20 resting on the bore 10 of said block and a bore 21 in said valve, and the stem 16 projects slightly beyond the end of the cup 8.

The cup 9 has a chamber 22 therein of conical formation at 23 to form a seat for a conical valve 24 and the stem 25 of which is grooved or flattened at 26 and slidable in a bore 27 of said cup, a coil spring 28 being interposed between the valve and corresponding end of the block 4 and guided by means of a rod 29 resting in the bore 10 of said block and a bore 30 in said valve, and the stem 25 projects slightly beyond the end of the cup 9.

To fill the cups with the desired liquids, one cup is unscrewed from the block 4, the valve preventing the liquid dropped into said cup from escaping therefrom, or the person filling the same may press a finger firmly against the outer end thereof to prevent leakage, the open end of the cup being uppermost, and, when filled, the block 4 may be screwed thereinto, and, this being repeated for the other cup, the device is ready for use.

I will provide means for distinguishing one cup from another, such as the numerals shown, whereby the particular liquid contained therein may be determined, and it will be seen that, if the valve stem of either of the cups be placed against the ink spot to be eradicated and slight pressure exerted on the container downwardly toward the ink spot, the valve is raised from its seat and the liquid passes through the vent of the cup, along the grooved or flattened side of the valve stem, and onto the ink spot, the degree of pressure determining the amount of liquid so discharged. After one liquid has been so discharged and sufficient time allowed for the chemical action thereof with the ink, the spot may be blotted in the usual manner and the other liquid used to entirely corrode and remove the ink spot.

In Fig. 1 I have shown two spring arms 31 secured to the cap 32 of a fountain pen

33, and each of which is provided with a trunnion or pintle 34 resting within the corresponding bore 11 of the flange 5, thus permitting revolution of the container in the frame so formed, and I have shown a rib 35 on the inner surface of each arm adapted to enter a corresponding slot 12 in said flange to lock the container against accidental displacement, but any other means 10 for locking the container may be employed, and said container may be mounted upon other articles than fountain pens, and in any desired manner, but the combination of an ink eradicator carrier with a fountain 15 pen is logical to say the least; I may also, as shown, secure a clip 36 to the arm or arms 31 to hold the combination in the pocket, and which clip may be of any desired form.

20 The device, as illustrated, is of the approximate diameter of the fountain pen cap, and of inconsiderable length when the advantages are considered, but, obviously, I do not limit myself to the size, shape, material, 25 or specific construction of the container, nor to its particular combination with any other article, although I do claim its use as shown.

Having fully described my invention, what I claim as new, and desire to secure by 30 Letters Patent, is:—

1. A device of the class described, comprising a block provided with an axial bore at each end and an external screw thread at each end, a cup detachably engaged with each threaded end provided with a conical outer end and a discharge bore in said conical end, a rod seated in each axial bore, a conical valve slidably mounted on each rod provided with a stem closely fitting within the re-

spective discharge bore, and a coil spring 40 interposed between each valve and the respective block end.

2. A device of the class described, comprising a block provided with an axial bore at each end and an external screw thread at 45 each end, a cup detachably engaged with each threaded end provided with a conical outer end and a discharge bore in said end, a rod seated in each axial bore, a conical valve slidably mounted on each rod provided 50 with a stem closely fitting within the respective discharge bore and flattened at one side intermediate its ends, and a coil spring interposed between each valve and the respective block end.

3. A device of the class described, comprising a central block, a cup in detachable connection with each end thereof having a discharge bore therein, a valve in each cup provided with a stem projecting beyond said cup, yielding means for maintaining said valves against their seats, a fountain pen cap, spring arms secured thereto and provided with lateral trunnions arranged on the same transverse axis and with ribs adjacent said trunnions, said block having diametrically arranged lateral bores therein adapted to receive the respective trunnions and having slots therein adapted to receive said ribs, whereby said device may be reversed end for 60 end and be locked in each position.

In testimony whereof I have signed my name to this specification in the presence of two subscribing witnesses.

KENNETH WILLIAM MACPHERSON.
